P. S. COHEN,

PLAYING CARDS.

APPLICATION FILED FEB. 7, 1916.

1,243,263.

Patented Oct. 16, 1917.

2 SHEETS—SHEET 1.

Fig. 1.

Fig. 2.

Fig. 3.

Witnesses

J.P. Tamm
R.L. Parker

P.S. Cohen, Inventor

by C. A. Snow & Co.
Attorneys

P. S. COHEN.

PLAYING CARDS.

APPLICATION FILED FEB. 7, 1916.

1,243,263.

Patented Oct. 16, 1917.

2 SHEETS—SHEET 2.

Witnesses

J.P. Donleavy
R.L. Parker

P. S. Cohen, Inventor

by Cadno & Co.

Attorneys

UNITED STATES PATENT OFFICE.

PHILLIP SEYMOUR COHEN, OF BOSTON, MASSACHUSETTS.

PLAYING-CARDS.

1,243,263.

Specification of Letters Patent. Patented Oct. 16, 1917.

Application filed February 7, 1916. Serial No. 76,692.

To all whom it may concern:

Be it known that I, PHILLIP S. COHEN, a citizen of the United States, residing at Boston, in the county of Suffolk and State 5 of Massachusetts, have invented new and useful Playing-Cards, of which the following is a specification.

The present invention appertains to games, and aims to provide a novel game, 10 16 denominated "Creation," which is fascinating as well as instructive.

The invention is illustrated in the accompanying drawings, wherein:—

Figure 1 is a view of the "Creator" card.

15 Fig. 2 is a view of the "animal creation" suit, composed of "animal" cards headed by a "man ruler" card.

Fig. 3 is a view similar to Fig. 2 of the "bird creation" suit, composed of "bird" 20 cards headed by a "woman ruler" card.

Fig. 4 is a view similar to Figs. 2 and 3, of the "articulata creation" suit composed of "articulata" cards headed by a "boy ruler" card.

25 Figs. 5, 6, 7 and 8 illustrate the "fish creation" suit composed of "fish" cards headed by a "girl ruler" card.

Fig. 9 is a view similar to Figs. 2, 3 and 4 of the "reptile creation" suit composed of 30 "reptile" cards headed by a "Satan ruler" card.

In order that the game can be more thoroughly understood, it is deemed appropriate to simply copy the rules and instructions as 35 copyrighted by applicant, but before doing this, a brief explanation of the cards will no doubt prove of assistance. The "Creator" card 1 illustrated in Fig. 1 contains an appropriate picture or representation together with a relative value numeral (50) and the legend "Creator," this card being 40 preferably colored gold. The "ruler" cards which head the various "creation" suits are designated 2, 3, 4, 5 and 6, and are "animal 45 ruler," "bird ruler," "articulata ruler," "fish ruler" and "reptile ruler" cards respectively, containing the respective pictures or representations of a man, woman, boy, girl and Satan. The "animal ruler" card heads the 50 suit of "animal creation" cards 7 each containing the picture and name of an animal and a relative value numeral, the picture of the highest card 7 only being illustrated in Fig. 2. The "animal creation" cards 2 and 55 7 are preferably colored red. The next suit is the "bird creation" suit headed by the "bird ruler" card 3, and composed of "bird creation" cards 8. The cards 3 and 8 are preferably colored blue, and each of the cards 8 carries a suitable picture or representation of a bird, together with a proper legend and relative value numeral. The "articulata ruler" card 4 heads the "articulata creation" cards 9, the cards 4 and 9 being preferably colored purple, and each 60 of the cards 9 containing a suitable picture or representation of an articulata, either vertebral or invertebral, together with a suitable legend and relative value numeral. This suit is preferably denominated the 65 "articulata creation" in preference to "insect creation," so as to include the most important creatures of both the vertebral and invertebral. Ranking next in importance is the "fish creation" suit composed of cards 75 10 headed by the "fish ruler" card 5, the cards 5 and 10 being preferably colored green, and each of the cards 10 carries a suitable picture or representation of a fish, together with a proper legend and relative 80 value numeral. The last suit is the "reptile creation" suit composed of cards 11 headed by the "reptile ruler" card 6, the cards 6 and 11 being preferably colored black, and each card 11 carries a suitable picture or representation of a reptile, together with a suitable legend and relative value numeral. Although only a few of the cards have been 85 illustrated in full, that is, to expose the pictures thereon, it is to be understood that all 90 of the cards can be provided with suitable pictures or representations, and the color scheme and illustrations may be varied, 95 within the scope of what is claimed, without departing from the spirit of the invention. The particular animals, birds, articulata, fish and reptiles chosen may be changed, as well as the relative value numerals as may be found more appropriate.

The following is a copy (with the exception of the use of the term "articulata" instead of "insect") of the instructions and rules entered according to act of Congress in the year 1915, by applicant, in the Office of the Librarian of Congress, at Washington, 105 which will give a thorough explanation of the game:—

The game of "Creation" is played with 106 cards and can be played by 2, or more players. When played by more than 4, the 110 number of players should be divided into equal sides if possible, if the number of players are uneven, then each one plays for himself. The more scientific and interesting results however, will be obtained with 4 persons playing as partners.

5 By a little study the game can be made very scientific by adults, and for children will be found not only entertaining, but highly instructive. To illustrate this fact, that the game (though scientific) is not beyond the children of even a tender age, the author's little daughter (9 years old) and son (10½ years old) have played with him and his wife, as partners, and changing around, partners themselves, yet no matter how the chance of partnership fell, it did not bother them in the least, proving their ability to readily master the game. In fact, the children themselves have suggested some excellent methods of play which after a thorough testing have been embodied in the rules. The knowledge of the children, in reference to the various creations used in the game, has been greatly enhanced as to the relative value, power, size and uses of the various creatures used to compose this fascinating game.

The "terms" used in the game are nearly all allegorical of the creation plan and it was with all due reverence that our Creator was placed in the game as the Supreme—over all. The Creator of the Creations. As the Creator rules over all—the one great power of the universe—the author did not deem it reverent to place a distinctive creation with Him, as was done with the rulers.

Our Creator, we have crowned in the rays of gold, of the sun, the "Light of the Universe" (the Creator color being gold, different from all the rest).

28 The first of the rulers is man—ruler of the animal creation. The color scheme for which, is red—signifying "blood of mankind." Next in power as a ruler, comes woman—ruler of the bird creation. Her ruling color being blue—signifying "faithful—heavenly." Appropriate color for man's "good angel" and the birds, whose home is the blue-sky. Naturally, the next ruler in power is man's and woman's first offspring—boy—ruler of the articulata creation. The color scheme for the boy being purple—which signifies "dignity—wealth—power." As wealth and power spring from the earth, even the lowly earth-worm, standing powerfully between mankind and starvation, it seemed fitting that the articulata those "multum in parvo's" should be chosen for the subjects of the boy. Naturally, next in power as a ruler, comes the girl—ruler of the fish creation. The color scheme for her is green—signifying "tender—flourishing." Could our little mermaid have more fitting subjects, than the fish? Where nature has placed them. In the green waters. Last of the rulers, and least in power, we have placed Satan—the "Prince of Darkness." Ruler of the reptile creation. The color for him is black signifying "gloom." As our foremother Eve first met Satan traditionally, as a reptile, the reptile creation for him seems most appropriate. As theology teaches us that mankind has the power to choose between "good and evil" in this life, and, as his Satanic Majesty seems to have so much to do in the creation scheme, it did not seem complete to leave him out; but, over him in power, are all of the other rulers—girl—boy—woman—man—as all have the power to resist him, if they choose. Thus, we have represented the greatest power for good, our Creator, the human family, and the evil-power—Satan.

The author has endeavored to employ terms indicative of the creative system, as far as possible, rather than the usual card-game terms. That players may more comprehensively follow the terms used in this game, we have set down in parallel columns, under proper headings, in comparative form, both terms.

"Creation" terms.	Card-game terms.	90
Creator	Joker
Ruler	Ace	95
Power	Trumps
Creation	Suit
Creatures	Cards
Universe	Pack
Genera	Hands
Cycle	Once-around	100
Prey	Trick
Attack	Leading
Distribution	Dealing
Distributer	Dealer
Partition	Cutting	105
Take	Draw
Haunt	Book
Capture	Winning trick
Offends	Revoke

Explanatory of "creation" terms used.

Creator—Supreme power over all, counting 50 when played after completing a haunt.

Rulers—Rank and count as follows—man—25, woman—24, boy—23, girl—22, Satan—21.

Power—The creation exposed by the distributer. (See Rule 2—Sec. A.)

Creations—Animals, birds, articulata, fishes, reptiles.

Creatures—There are 20 creatures in each creation, and rank from 20 down to 1, and are numbered in accordance with their rank, their value being governed by the index number in the corner of each.

Universe—The remaining creatures left after the distribution. (See Rule 4—Sec. A.)

Genera—The 15 creatures which are held by each player. (See Rule 2—Sec. A.).

Cycle—The complete exhaustion of all creatures in the universe and the genera after each distribution.

Prey—The playing of creatures—(generally termed a "trick.")

Attack—The creature stalking a prey.

Capture—The winning of a prey.

10 Distribution—Passing out the proper number of creatures to each player.

Distributer—The player making the distribution. (See Rule 1.).

15 Partition—Dividing the universe to see who shall be the 1st. distributer.

Take—The manner of replenishing the genera. (See Rule 4—Sec. A.).

20 Haunt—The number of preys necessary to be captured before the player can start scoring. Ordinarily termed "books." (See Rule 6—Sec. A.).

Offends—Breaking any of the rules, commonly known as "revoking."

25 Object of the game.

To create a haunt as quickly as possible, as each creature in every capture made thereafter, counts in scoring, just as many points as the number indicated in its corner. The player (or partners) with the highest total number scored wins.

The finality of the game being determined only after each player participating has had one turn at distribution.

30 RULES GOVERNING PLAY.

Rule—One.

Distributer.—Each player shall partition the universe to see who shall win the first distribution. The player who shows the highest in rank—wins. Ranking—Creator, man, woman, boy, girl, Satan, creatures down to 1. Ties try over, only, where 45 neither Creator nor rulers are partitioned.

Rule—Two.

Distribution.

50 Sec. A.—Creatures shall be distributed to the left, and so on in turn, the distributer last, until every player has 15 creatures. The last creature distributed (the distributer's) must be turned face up, and left there until the distributer's turn to play, and is not subject to forfeiture. The creation thus exposed shall be the power-creation for that cycle.

Sec. B.—Should the "Creator" be faced up, then the distributer shall without looking at his genera, name some creation to be the power-creation for that cycle.

Sec. C.—Each player shall distribute in turn. Order of distribution being to the left.

Rule—Three.

Adjustment.—As there are 100 creatures, 5 rulers, and the "Creator," totaling 106 in all, which constitutes the universe, if 3 or 5 are playing, the distributer, after making the power-creation for that cycle, shall take one creature from the top of the universe and add it to his genera and then put away any one from his genera that he desires with the first prey (before the play starts,) in order to make the take come out even thereafter. If 4 persons are playing, the distributer takes 2, in the same manner. If more than 5 are playing an adjustment must be regulated by mutual agreement before the distribution starts.

Rule—Four.

The take.

Sec. A.—After Rules 1, 2 and 3 have been complied with, the player to the left of the distributer stalks a prey. After the capture has been completed the player winning it takes one from the universe. The players to the left, each in turn, do likewise, until all have had a take, thus each genera is kept intact with 15 creatures until the universe is exhausted.

Sec. B.—If a player has too many, or too few creatures, after the 1st take, the opponents have the privilege of allowing the player in error to play without taking until his genera is reduced to the proper number, if too many, or to fill his genera if he has too few, or call for a new distribution, voiding the cycle wherein offense occurs.

Rule—Five.

Genera.

Sec. A.—After the universe is exhausted, play shall continue as before until the last creature has been played from every genera.

Sec. B.—No player is permitted to lay down their genera in surrender without forfeiture of the game, unless by mutual agreement of all concerned. All generas must be played out to the last creature.

Rule—Six.

Haunt.

Sec. A.—When 2 persons are playing, 20 preys constitute a haunt.

When 3 or 4 persons are playing, 10 preys constitute a haunt.

When more than 4 are playing, 5 preys constitute a haunt.

Sec. B.—The value of each and every creature capture in excess of a haunt shall be added together and the total placed to the credit of the side capturing them at the termination of each cycle, at face value, toward the final result.

70

75

80

90

95

100

105

115

120

130

Rule—Seven.Prey.

Sec. A.—The highest creature played in 5 the same creation as the one starting the prey, makes the capture unless a power-creature, ruler or the creator is played.

Rule—Eight.

10

Creations.

Sec. A.—Whatever creature is used to open a prey with, it is obligatory upon 15 every player to play the same creation if possible.

Sec. B.—If a player has none of the creation 20 played, then they are at liberty to play what they please.

Sec. C.—Whenever a power-creature starts a prey and a subsequent player has 25 none, but has any of the rulers, a ruler must be played. All rulers are part of the power-creation. (See Sec. A. of Rule 10.)

Sec. D.—If a player has other powers, he 30 may use a ruler if preferable.

25

Rule—Nine.Creator.

Sec. A.—The "Creator" being supreme 35 over all, will capture any prey upon which it is played and may be held or played at will to suit the holder.

Sec. B.—Should a player start a prey, by 40 playing the "Creator," the player must at once name the creation he wishes to call forth, whereupon each player in turn shall play his highest in the creation called for (the ruler included). Should any player not hold any of the creation called for; yet, 45 hold any of the power-creation, then he must play his highest power-creature, (ruler included). Should any player hold neither the creation called, nor a power, nor a ruler, then they may play as they like.

Sec. C.—When playing the "Creator" upon 50 a prey previously started by some other player, the player playing it, does not name any creation.

Sec. D.—Should a player start a prey by 55 playing the "Creator" and by oversight neglect to name some creation, the second player in turn (noting the over-sight) may lay down any creature he pleases, at the same time pick up the "Creator" and place 60 it in his own genera, and hand from his genera, to the original player of the "Creator," any creature he pleases, (the first player thus automatically becomes the last in this play) and all players must (if possible) follow the creation played by the second player. Should the second player overlook his opportunity before playing the privilege passes onto each player in turn, but cannot be claimed out of turn. Removing 65 the hand from a creature played without naming some creation, shall forfeit that player's right in the play.

Rule—Ten.Rulers.

70

Sec. A.—The ruler of each creation is always a power and is, not only above his own creatures, but also, above all other creatures in any other creation, therefore will capture and prey upon which played, 75 unless overpowered by some ruler of higher rank. No creature, even of the power-creation can capture a ruler.

Sec. B.—When a player starts a prey with a ruler, other than the power-creation ruler (all rulers being powers) the player may call for the power-creation, if this is done, other players are obliged to follow if possible with power-creatures, but they are not called upon to play their highest (as in Sec. 80 B—Rule 9; or Sec. E—of Rule 10). In this instance a player may play as low a power-creature as desired, though if holding another ruler of higher rank they are entitled to play it, if they wish to make 90 capture.

Sec. C.—Should a player call for the power-creation with some ruler (as allowable, see Sec. B—Rule 10), and any player has no power-creatures, but has any of the 95 other rulers, a ruler must be played.

Sec. D.—Should a player call for the power-creation with a ruler, any player have no power-creatures, that player is not called upon to play in the creation of which that 100 ruler is the head, for no ruler can involve two different creations in the same prey. Only the "Creator" can involve two creations at one prey. (See Sec. B—Rule 9).

Sec. E.—Any player may start a prey 105 with a ruler and call for the highest (in that creation only of which that ruler is the head), by announcing, "I want the highest fish" (or whatever the creation is) and thus force out the highest in that creation only, 110 but should a player not make the formal demand for the highest, no player is obliged to play his highest, nor to play a power-creature as in this instance such ruler is held to his own creation.

Sec. F.—In no case can any player be 115 compelled to play a power-creature in any prey where a ruler opens the attack and does not call for the power creation, but he must follow the creation if possible, if he cannot 120 then he may play what he pleases.

Sec. G.—When a player has only the ruler of the creation played in opening a prey, he may (in this instance only), if he chooses, in order to guard his ruler, play a power-creature, but if he has no power-creatures, then he must play that ruler.

Sec. H.—Should a player however, hold other creatures in the creation played, in addition to the ruler, then a power-creature 130 cannot be substituted (as Sec. G above). Here the ruler has natural guards.

Rule—Eleven.

5

Offense.

Sec. A.—Any player who fails to comply with any and all sections of Rules 7—8—9—10 offends. Whether by accident or intent.

Sec. B.—A player who offends shall surrender to his opponent (the one who calls attention to the offense), not only the offending prey; but also all subsequent captures made between the offense, and up to, and including the capture at the time the offense is called.

Sec. C.—Any player offending, may correct the error before the capture is placed in a haunt. In such a case the player's adversaries may, if they desire, change their play, but his partner cannot.

Sec. D.—It is obvious that section A of Rule 8, and section B of Rule 11, cannot be enforced while the universe remains to be taken from, as at the time of play a player might not have, a fish say; yet, in the very next take from the universe may receive one, so while the universe remains unexhausted the honor of the players must be relied upon.

Having thus described the invention, what is claimed as new is:

1. A pack of playing cards for playing an allegorical game of creation instructive as to the classes, order and values of creatures, composed of suits each having a "ruler" card and other cards bearing representations and legends of creatures of one class different from the other suits, the cards of each suit bearing value numerals proportional to the power and size of the various creatures represented.

2. A pack of playing cards for playing an allegorical game of creation instructive as to the classes, order and values of creatures, composed of suits each having a "ruler" card and other cards bearing representations and legends of creatures of one class different from the other suits, the cards of each suit bearing value numerals proportional to the power and size of the various creatures represented, the "ruler" cards bearing representations of different human beings and bearing value numerals greater than the other cards and differing from one another according to the value and power of the human beings represented.

3. A pack of playing cards for playing an allegorical game of creation instructive as to the classes, order and values of creatures, composed of suits each having a "ruler" card and other cards bearing representations and legends of creatures of one class different from the other suits, the cards of each suit bearing value numerals proportional to the power and size of the various creatures, represented, and a controlling card representing the Creator.

4. A pack of playing cards for playing an allegorical game of creation instructive as to the classes, order and values of creatures, composed of suits each having a "ruler" card and other cards bearing representations and legends of creatures of one class different from the other suits, the cards of each suit bearing value numerals proportional to the power and size of the various creatures represented, the "ruler" cards bearing representations of different human beings and bearing value numerals greater than the other cards and differing from one another according to the value and power of the human beings represented, and a controlling card bearing a representation of the Creator and a value numeral greater than those of the "ruler" cards.

5. A pack of playing cards representing the universe for playing an allegorical game of creation instructive as to the classes, order and values of creatures, composed of suits representing different creations and having "ruler" cards bearing representations of man, woman, boy, girl and Satan, respectively, and other cards having representations and legends of animals, birds, articulata, fish and reptiles, respectively, the cards of each suit bearing value numerals proportional to the power and size of the various creatures represented.

6. A pack of playing cards representing the universe for playing an allegorical game of creation instructive as to the classes, order and values of creatures, composed of suits representing different creations and having "ruler" cards bearing representations of man, woman, boy, girl, and Satan, respectively, and other cards having representations and legends of animals, birds, articulata, fish and reptiles, respectively, the cards of each suit bearing value numerals proportional to the power and size of the various creatures represented, the "ruler" cards bearing value numerals greater than those of the other cards and differing from one another according to the value and power of the rulers represented, and a controlling card representing the Creator and bearing a value numeral greater than those of the aforesaid cards.

In testimony that I claim the foregoing as my own, I have hereto affixed my signature in the presence of two witnesses.

PHILLIP SEYMOUR COHEN.

Witnesses:

FRANK MALONEY,
CHAS. E. CARVER.